UNITED STATES PATENT OFFICE.

LAMBERT ZEIGLER, SR., OF LYONS, IOWA.

WOODWORKING-MACHINE.

No. 839,691.

Specification of Letters Patent.

Patented Dec. 25, 1906.

Application filed May 24, 1906. Serial No. 318,569.

To all whom it may concern:

Be it known that I, LAMBERT ZEIGLER, Sr., a citizen of the United States, residing at Lyons, in the county of Clinton and State of Iowa, have invented a new and useful Woodworking-Machine, of which the following is a specification.

This invention relates to tables for wood-working-machines, and has for its object to provide a sectional table, the parts of which can be adjusted to different elevations in relation to each other and to the supporting-frame of the table, whereby the panels or other stock to be operated upon can be held firmly in place even though their surfaces be of irregular contour.

In woodworking-machines utilizing scoring-knives and cutter-heads it is desirable not only to have a table which will hold the stock firmly in place even though it be warped, but it is also necessary to have simple means whereby the stock can be quickly adjusted toward or away from the cutting mechanism of the machine.

25 One of the objects of the invention is to provide simple and efficient means for obtaining this result.

With the above and other objects in view the invention consists of certain novel features of construction and combinations of parts which will be hereinafter more fully described, and pointed out in the claims.

In the accompanying drawings is shown the preferred form of the invention.

35 In said drawings, Figure 1 is a front elevation of a table constructed in accordance with the present invention, a cutter-head being shown in position beneath the table. Fig. 2 is a view, partly in plan and partly in horizontal section, of the table-sections and of the adjoining portion of the supporting-frame, only a part of the outer table-section being shown. Fig. 3 is a section on line *a a*, Fig. 1. Fig. 4 is a section on line *b b*, Fig. 1, showing only a portion of the outer table-section and of the supporting-frame. Fig. 5 is a section on line *c c*, Fig. 1. Fig. 6 is a plan view of one of the slides of the supporting-strips, and Fig. 7 is a detail view of a supporting-strip.

Referring to the figures by characters of reference, 1 is a supporting-frame of any suitable construction, on which is disposed a bed 2, having an enlarged central opening 3.

55 Mounted upon cross-strips 4, connecting

the sides of the supporting-frame near the bottom thereof, are standards 5, in which is journaled a shaft 6, having beveled gears 7 at the ends thereof and meshing with similar gears 8, secured upon vertical shafts 9 and 10, respectively. These shafts are journaled at their lower ends in the cross-strips 4, and the shaft 9 is provided at its upper end with a crank 11, whereby the shaft may be rotated manually. Each shaft 9 and 10 has a screw-threaded portion 12, and these threaded portions extend through and engage ears 13, which extend inwardly through the side of the supporting-frame and from a base-slide 14, which is mounted upon said side of the frame. It is therefore obvious that whenever the shaft 9 is rotated, as by means of the crank 11, the threaded portion 12 thereof will move the ear 13 longitudinally thereof, and at the same time rotary motion will be transmitted through shaft 6 to shaft 10, so that the ear 13 will be moved longitudinally of said shaft 10. Both ends of the base-slide can therefore be adjusted upward and downward simultaneously by an operator standing adjacent the crank 11. A slot 15 is formed within the central portion of the base-slide. Arranged upon the inner face of the base-slide 14 are guide-cleats 16, between which is mounted a slideable bracket 17, having guides 18 disposed on the top thereof and engaging a slide 19, on which is mounted a rotatable shaft 20, carrying a pulley 21. An ear 22 extends upward from the free end of the bracket, and mounted within it is an adjusting-screw 23, which is swiveled in the slide 19, and by manipulating this screw said slide can be moved longitudinally upon the bracket. A cutter-head 24 is secured to that portion of the shaft 20 which projects through the side of the frame, and it is obvious that when the pulley 21 is rotated, by means of a belt 25 driven by any suitable power, this head will be rapidly revolved. By turning the screw 22 in either direction the entire shaft can be adjusted longitudinally, so as to move the cutter-head toward or away from the base-slide. A guide-bolt 26 extends from the brackets 17 and through the slot 15, said bolt being provided with a head 27, which overlaps the walls of the slot. This bolt constitutes a guide for the bracket and at the same time holds it tightly against the base-slide. In order that the base-slide may be retained in proper relation with the

side of the supporting-frame 2, guide-cleats 28 are secured thereto or formed therewith and overlap the walls 29 of the large front opening 30 within the side of the supporting-frame 2. It will therefore be seen that the base-slide and the bracket 17 connected thereto can be readily adjusted by means of the shaft 9 and the parts operated thereby, and an independent vertical adjustment of said bracket 17 is attained by means of an adjusting-screw 31, which bears upon the bottom of the bracket 17 and is screwed through an ear 32, extending inwardly from the base-slide, as shown particularly in Figs. 1 and 3.

Extending from the ends of the base-slide 14 are brackets 33, supporting the intermediate table-sections 34 and provided at their front ends with alining flanges 35. A space 36 is formed between the table-section 34 and the base-slide 14, and projecting beyond the flanges 35, with its upper face flush with the top of the table-section 34, is a tongue 37, having its lower face formed with an angular recess 38. One of the flanges 35 has a portion of its lower edge inclined, as shown at 39, and provided with an ear 40, in which is mounted an adjusting-screw 41. This adjusting-screw bears against an ear 42, which extends from the base-section 43 of the outer table-section 44. Two of these base-sections are employed, one near each end of the table, and brackets 45 connect the base-sections with the table-sections. Angular tongues 46 are formed upon the base-sections 43 and partly overlap the inner edge of the table-section 44, and these tongues are adapted to be seated within the groove 38, so as to bind the table-sections 34 and 44 tightly together.

Parallel inclined slots 47 are formed in the two base-sections 43, and projecting through these slots are guide-bolts 48, which extend from the flanges 35. It will be understood from the foregoing that by rotating the screw 41 within ear 40 the base-sections 43 of the outer table-section 44 can be raised or lowered in the direction of the diagonal slots 47, so as to lift the table-section 44 into position (shown in Figs. 3 and 4) or to lower said table-sections to a desired point in relation to the intermediate section 34. Guide-cleats 49 are arranged in pairs upon the outer face of the base-slide, and mounted between each pair of these cleats is a slide 50, having an outwardly-extending ear 51, bearing upon an adjusting-screw 52. These adjusting-screws extend through ears 53 upon the base-slide, and by turning said screws the slides can be moved upward or downward. Each slide 50 has an outwardly-extending flange 54, provided with longitudinally-extending slots 55, and slidably mounted on the two slides 50 and their flanges 54 are supporting-strips 56, which extend between the table-section 44 and the base-slide and have outwardly-ex-

tending flanges 57, from which extend guide-bolts 58, which are slidably mounted in the slots 55. These supporting-strips have their adjoining ends undercut or beveled, as shown at 59, so that if the cutter-head is not 70 in use the two supporting-strips can be slid toward each other, so as to bridge over said cutter-head. It is of course understood that an opening 60 is formed within the intermediate table-section 44 to permit the cutter- 75 head to be adjusted upward or downward therethrough.

What is claimed is—

1. In a woodworking-machine, the combination with a supporting-frame and a table-section extending laterally from said frame and spaced therefrom at the top; of guide-cleats upon the supporting-frame, slides mounted between said cleats, means for adjusting the slides vertically upon the supporting-frame, an outwardly-extending flange at the upper end of each slide, supporting-strips interposed between the top of the table-section and the supporting-frame, outwardly-extending flanges thereon and bearing on the flanges of the slides and adjustable longitudinally thereon, and means for securing said supporting-strips in adjusted position upon the slides. 80

2. In a woodworking-machine, the combination with a supporting-frame; of a slide mounted upon one side thereof, means for simultaneously adjusting the end portions of the slide upon the frame, an intermediate table-section carried by and spaced from the slide, guide-cleats upon the slide, independently-adjustable slides mounted between the cleats, supporting-strips interposed between the table-section and the frame and bearing on the independently-adjustable slides, said strips being movable longitudinally on said slides, and means for locking the strips in adjusted position upon their supporting-slides. 90

3. In a woodworking-machine the combination with a supporting-frame; of a base-slide mounted upon one side of the frame, adjusting devices engaging opposite portions of said slide, means for actuating said devices simultaneously from one end of the frame, an intermediate table-section movable with the base-slide, flanges depending from said intermediate table-section, an outer table-section, brackets thereunder and movably mounted on the flanges, said brackets having inclined slots therein, guide devices extending from the flanges and through the slots, and means engaging the flanges and bearing upon the brackets for adjusting said brackets in the direction of the length of the slots. 110

4. In a woodworking-machine the combination with a supporting-frame; of a base-slide mounted upon one side of the frame, adjusting devices engaging opposite portions of said slide, means for actuating said devices simultaneously from one end of the frame, an 120

intermediate table-section movable with the base-slide, flanges depending from said intermediate table-section, an outer table-section, brackets thereunder and movably mounted 5 on the flanges, said brackets having inclined slots therein, guide devices extending from the flanges and through the slots, means engaging the flanges and bearing upon the brackets for adjusting said brackets in the direction of the length of the slots, and a tongue

integral with each bracket and adapted to engage the intermediate table-section.

In testimony that I claim the foregoing as my own I have hereto affixed my signature in the presence of two witnesses.
